(57) **CLAIM**

I claim the ornamental design for an embossed socket for garden tool, as shown and described.

DESCRIPTION

FIG. 1 is an isometric view of an embossed socket for garden tool.

FIG. 2 is a front view of an embossed socket for garden tool.

FIG. 3 is a back view of an embossed socket for garden tool.

FIG. 4 is a right side view of an embossed socket for garden tool; and,

FIG. 5 is a left side view of an embossed socket for garden tool.

The broken line showing of the garden tool is included for the purpose of illustrating borders and forms no part of the claimed design.
